UNITED STATES PATENT OFFICE.

WALTER E. FIELD, OF PROVIDENCE, RHODE ISLAND, ASSIGNOR TO T. E. BENNETT COMPANY, OF PROVIDENCE, RHODE ISLAND, A CORPORATION OF RHODE ISLAND.

DESIGN FOR A BROOCH.

41,174.

Specification for Design.

Patented Feb. 14, 1911.

Application filed November 22, 1910. Serial No. 593,758. Term of patent 7 years.

To all whom it may concern:

Be it known that I, WALTER E. FIELD, a citizen of the United States, residing at Providence, in the county of Providence and State of Rhode Island, have invented a new, original, and ornamental Design for a Brooch, of which the following is a specification, reference being had to the accompanying drawing, forming part thereof.

The figure is a face view of my design for a brooch.

I claim:

The ornamental design for a brooch, as shown.

WALTER E. FIELD.
